UNITED STATES PATENT OFFICE.

ARGYLE R. BUTTER, OF EAST PITTSBURGH, PENNSYLVANIA, ASSIGNOR TO WESTINGHOUSE ELECTRIC & MANUFACTURING COMPANY, A CORPORATION OF PENNSYLVANIA.

ELECTRICAL MEASURING INSTRUMENT.

Application filed March 12, 1926. Serial No. 94,189.

My invention relates to electrical measuring instruments and particularly to the magnetizable core member of watt-meters and other similar motor meters.

5 One object of my invention is to provide a measuring instrument, of the above-indicated character, that shall be exceedingly simple, compact, and light in construction and easy to manufacture.

10 Another object of my invention is to provide a measuring instrument, of the above-indicated character, that shall have its magnetizable core member provided with interfitting portions to facilitate assembly.

15 In my invention a dove-tailed perimetral segment is provided for the magnetizable core member, which is pressed into operative position with respect to the core member after the series or current coil of the motor-20 meter is wound or placed in position.

In the prior art, magnetizable core members of substantially the same shape have been provided with no removable portions rendering the winding of coils thereon very 25 difficult.

30 In a motor-meter embodying my invention a laminated base portion is punched out separately from the remainder of the laminated magnetizable core member to expose the polar-projections in such position that they may be easily wound with the necessary coils. The base portion is subsequently 35 pressed into position.

The single figure of the accompanying 35 drawing is a front elevational view of the motor-meter embodying my invention.

40 A motor-meter of the above mentioned character comprises, in general, a laminated magnetizable core member 1, having a removable base portion 2, and a series or current winding 3.

45 The magnetizable core member 1 is constructed of a plurality of continuous laminations, having, a central portion 5 and side portions 6 and 7 that are integral with the outer portion 4 at one end and spaced apart from each other at their free ends by air-gaps 8 and 9. A slot 10 is provided near the free end of the central portion 5 and the 50 side-portions 6 and 7 are provided with laterally extending horns 11 and 12, respectively. The series or current winding 3 is disposed around the spaced-apart ends of the members 5, 6, and 7.

The base portion 2 which comprises the 55 lower portion of the core member 1 is punched out separately from a plurality of continuous laminations. Both ends of the base portion 2 are provided with dovetails 13 and 14 to fit into suitable recesses punched 60 in the lower extremities of outer portion 4. After the series or current coil 3 is wound on the polar projections 5, 6, and 7, the base portion 2 is pressed into place by forcing the dovetails 13 and 14 into the receptive recesses on the lower extremities of outer portion 4.

65 By punching the core member 1 in two portions means are provided to greatly facilitate the winding of the series or current 70 coil 3. When the two portions are joined together the resulting complete core members 1 has all the advantages of a one-piece core member.

75 I claim as my invention:

1. A lamination comprising a plurality of magnetizable members, one of said members comprising pole portion structure, another of said members comprising a section forming with said pole portion structure a flux 80 gap for the reception of a movable meter disc, said members being secured together in interlocking relation and being non-detachable in a direction extending at right angles to the plane of said meter disc. 85

2. A lamination comprising a plurality of magnetizable members, one of said members comprising pole portion structure, another of said members comprising a section forming with said pole portion structure a flux 90 gap for the reception of a movable meter disc, said members being secured together in dovetail relation and being non-detachable in a direction extending at right angles to the plane of said meter disc. 95

3. A lamination comprising a plurality of magnetizable members, one of said members comprising a plurality of spaced pole portions, another of said members comprising a section forming with said pole portions a flux 100 gap for the reception of a movable meter disc, said members being secured together in interlocking relation and being non-detachable in a direction extending at right angles to the plane of said meter disc. 105

4. A lamination comprising a plurality of magnetizable members, one of said members comprising a plurality of spaced pole por-

tions, another of said members comprising a section forming with said pole portions a flux gap for the reception of a movable meter disc, said members being secured together in 5 interlocking relation and being detachable only by moving them relatively in a direction extending substantially parallel with the plane of said meter disc.

5. A magnetizable structure comprising a 10 plurality of groups of stacked laminations, one of said groups comprising a plurality of spaced pole portions, another of said

groups comprising a section forming with said pole portions a flux gap for the reception of a movable meter disc, said groups 15 being secured together in interlocking relation and being non-detachable in a direction extending at right angles to the plane of said meter disc.

In testimony whereof, I have hereunto subscribed my name this 5th day of March, 1926.

ARGYLE R. RUTTER.
